SHEAR POLEHEAD

William H. Ealy, Wichita Falls, Tex., assignor to
Clark Machine Company, Wichita Falls, Tex.

Application March 13, 1937, Serial No. 130,745

3 Claims. (Cl. 254—139)

This invention relates to well spudding and drilling machines and it has particular reference to an improved shear pole head.

The principal object of the invention is to provide for the incorporation in the head of a shear pole, the casing sheaves, drilling sheave and sand line sheave in a single sturdy and compact unit and to so dispose the sheaves relative to the casing hole that the casing blocks will be at all times in perfect alignment with the hole. In this manner, the invention is effective in eliminating the necessity of changing the position of the shear poles when running casing.

Another object of the invention is to provide complementary castings, designed for association to uniformly distribute the strain normally imposed on the sheaves in operation.

With the foregoing objects as paramount, the invention has particular reference to its salient features of construction and arrangement of parts which will become manifest as the description proceeds, taken in connection with the accompanying drawing, wherein:

Figure 1 is a side elevation of a shear pole head constructed according to the present invention.

Figure 2 is a front elevation.

Figure 3 is a detail view in perspective of one of the shear pole castings, and

Figure 4 is a perspective view of another form of sheave mounting.

Continuing with a more detailed description of the drawing, portions of the shear poles 1 are shown in Figures 1 and 2 and comprise the mast or derrick of a portable spudding machine. The shear poles are constructed preferably of tubular material since such construction usually obviates much of the bracing otherwise necessary.

Mounted on each of the poles 1 is a casting 2. These castings are each comprised of an integral collar 3 to receive the end of the pole, with a flat bearing plate 4 thereon. The plate 4 is provided with a semi-cylindrical groove 5 to receive the shaft 6, carrying the series of casting sheaves 7, arranged between the castings 2 when operatively assembled.

In spaced relationship near the ends of the shaft 6 is provided annular grooves which correspond with the annularly disposed ribs 8 within the groove 5 in the bearing plate 4. The shaft is thus held against longitudinal displacement in its bearings.

To complete the bearings for the shaft 6, a crown member comprised of castings 9 is provided with corresponding bearing plate 10, similarly grooved and ribbed and which are secured

by means of bolts 11 to the plates 4 to embrace the ends of the shaft 6.

The crown member is constructed with an arched bridge 12, reinforced by webs 13 and extends upwardly and outwardly at a slight angle 5 with respect to the plane of the bearing plates 4 and 10. The castings 9, defining the bridge 12, are each provided with bearings 14 in which are journaled the ends of a stub shaft 15. The shaft 15 carries a single sand sheave 16.

Referring again to the shear pole castings 2, it will be noted in Figure 1 that each has an angular plate 17 on one side, reinforced by a web 18 thereunder. These plates are provided with semi-cylindrical, ribbed grooves 19 to receive the ends of 15 a shaft 20, which latter carries the large drilling sheave 21. Angularly disposed plates 21a are mounted at one end on the shaft 6 and engage the lower shaft 20 to afford a means to maintain the sheave 21 in a central position on the latter 20 shaft.

It will be observed that the peculiar construction and relationship of the elements of the shear pole head is such that the axes of the shafts 6, 15 and 20 are relatively offset, thereby avoiding 25 interference between the lines and the arrangement is especially useful in that the casing blocks are always in perfect alignment with the casing hole, which eliminates the necessity of changing the positions of the poles 1 when running casing. 30

In the form of the invention shown in Figure 4, the collars 22, comparable to collars 3 in the preceding figures, are provided with an apron 23 as an added reinforcement, since the weight is forward of the longitudinal axes of the shear 35 poles 24, on which the head is mounted.

The differentiating characteristics of the form shown in Figure 4, over the previously described shear pole head, lies in the fact that the shaft 25, carrying the drilling sheave 26, shown fragmentarily, is journaled in apertures in plates 27, cast integrally with the collars 22 while in the preceding instance, the ends of the comparable shaft lie in grooves and are held operatively therein by 40 bearing plates.

The remaining structure of the head shown in Figure 4, i. e., the upper casting 28, shaft 29 and its sheaves 30 are substantially the same, as well as the centering plates 31, comparable to plates 21a in Figure 2.

Manifestly, the construction as shown and described is capable of some modification and such modification as may be construed within the scope and meaning of the appended claims is also 55

considered to be within the spirit and intent of the invention.

What is claimed is:

- 5 1. A shear pole head comprising companion collar members receiving the ends of shear poles and having grooved bearing plates, a pair of arcuate members having bearing plates complementary to the plates of said collar members and disposed on the latter to embrace a shaft disposed in the grooves of said plates, said arcuate members likewise cooperating to support a second shaft whose axis is disposed above and forwardly of said first shaft, and a pair of plates integral with and extending forwardly from each 10 15 of said collar members and arranged to receive a third shaft whose axis is offset relative to that of said first and second shafts and a series of line sheaves disposed on said shafts.
2. A shear pole head comprising a body arranged to be mounted on a pair of spaced shear poles and carrying a centrally located shaft, a series of spaced sheaves mounted on said shaft, 20

means also carried by said body for retaining a second shaft above said first shaft, whose axis is parallel with but offset relative to the axis of said first shaft, and means extending from the lower portion of said body for supporting a third shaft whose axis is parallel with and offset relative to the axes of the companion shafts and sheaves mounted on said second and third shafts. 5

3. A shear pole head for well drilling and spudding machines comprising a body having upper and lower portions, collars arranged on the lower portion of said body to be mounted on a pair of shear poles, grooved bearing plates carried by said collars, a shaft journaled in bearings provided by said grooves, a series of casing sheaves 10 15 on said shaft, a shaft mounted in the upper portion of said body above and forwardly of said first shaft, a sand line sheave mounted thereon, a shaft journaled in the lower portion of said body below and forwardly of said first shaft and a 20 drilling sheave mounted on said latter shaft.

WILLIAM H. EALY.
